Des. 216,930
Patented Mar. 17, 1970

216,930

MULTIPLE PURSE

Murray Wolf, Union, N.J., assignor to Evans-Aristocrat
Industries, Inc., Elizabeth, N.J., a corporation of New Jersey

Filed Jan. 27, 1969, Ser. No. 15,522

Term of patent 14 years

Int. Cl. D3—02

U.S. Cl. D87—3

FIG. 2

FIG. 1

FIG. 3

FIG. 4

FIG. 5

FIG. 1 is a front view of a multiple purse showing my new design;

FIG. 2 is an edge view thereof;

FIG. 3 is a top plan view thereof;

FIG. 4 is a bottom view thereof; and

FIG. 5 is a rear view.

Both edges of the multiple purse have the same appearance.

I claim:

The ornamental design for a multiple purse, as shown and described.
